US00D993274S

(12) **United States Design Patent** (10) **Patent No.:** **US D993,274 S**
Scavo (45) **Date of Patent:** **** Jul. 25, 2023**

(54) **DISPLAY SCREEN OR PORTION THEREOF WITH GRAPHICAL USER INTERFACE FOR ALERTS**

(71) Applicant: **Nowcasting.ai, Inc.**, Palo Alto, CA (US)

(72) Inventor: **Damian Ariel Scavo**, Palo Alto, CA (US)

(73) Assignee: **Nowcasting.ai, Inc.**, Palo Alto, CA (US)

(**) Term: **15 Years**

(21) Appl. No.: **29/805,021**

(22) Filed: **Aug. 24, 2021**

(51) **LOC (14) Cl.** **14-04**

(52) **U.S. Cl.**

USPC **D14/486**

(57) **CLAIM**

The design for a display screen or portion thereof with graphical user interface for alerts, as shown and described.

DESCRIPTION

The FIGURE illustrates a front view of a display screen or portion thereof with a graphical user interface for alerts. The broken lines in the drawing illustrate portions of the article or environment that form no part of the claimed design.
